UNITED STATES PATENT OFFICE.

CHARLES STAFFORD WAKEFIELD, OF HAMPSTEAD, LONDON, ENGLAND.

TEMPORARY OR PORTABLE STRUCTURE OR BUILDING.

1,312,065.

Specification of Letters Patent. Patented Aug. 5, 1919.

Application filed February 4, 1919. Serial No. 274,923.

To all whom it may concern:

Be it known that I, CHARLES STAFFORD WAKEFIELD, a subject of the King of Great Britain and Ireland, residing at Hampstead, London, N. W. 3, England, have invented Improvements in Temporary or Portable Structures or Buildings, of which the following is a specification:

My prior United States patent application filed Feby. 1, 1918, Se. No. 214,861 describes building elements or sections constructed of laths of wood, metal or other material so secured together by a flexible backing of canvas or other material, that if curved or arched to form a roof or roof portion for example, the flexible backing being on the outer side, the longitudinal sides of the several laths bear one against the other and mutually support each other thereby rendering the element or section self-supporting, while for convenience of transport it can be rolled or folded into a body of relatively small compass.

According to the present invention the laths of wood, metal or other material are associated with relatively narrow bands or strips, or wire or other cables which are tightened to force the longitudinal edges of the laths toward each other independently of any supporting members in order to render the structure rigid. The bands, strips or cables may be made of canvas or of thin metal in the form of wire cable for example, or of any other appropriate material adapted to bear the strain or stress which is imparted to it when tightened to press the laths toward each other.

In order to render a building built up of the improved elements or sections weather proof and water tight there may be thrown over it a waterproof covering secured in place in any suitable manner. In some cases the waterproof covering is formed in lengths the edges of which when the cover is in place overlap, the said overlapping edges being if desired provided with beads or the like adapted to render the joints weather tight when the cover is drawn down securely in place.

The bands, strips, or cables, may be secured to the laths in any suitable way, for example by wire stitching, or by a water-

proof adhesive, or by clips, nails, screws or other devices, or may be passed through loops of canvas, metal or other material secured to the laths.

An advantage in passing the connecting bands, strips or cables through loops on the laths is that the laths can move toward and from each other and so automatically adjust themselves as necessary when they are forced into contact one with the other.

For convenience in transport the elements or sections designed to form a roof may if desired, be made in two or more parts arranged to be connected together by mutually engaging hooks or other devices.

Figure 1 of the accompanying drawings is a fragmentary view of a portion of a building section or element embodying the invention.

Fig. 2 is a sectional detail view showing one construction of means according to the invention for securing the lath sections or elements to the longitudinal floor joist of a building.

Fig. 3 is a sectional view illustrating a detail of construction to which reference will be hereinafter made.

In the construction shown in Figs. 1 and 2, the laths *a* arranged to form the sides and roof of a building as described in my prior United States patent application filed Feby. 1, 1918, Se. No. 214,861, are forced toward each other by means of wire cables *b* thrown over the building and secured to the laths by means of metal loops or wide staples *c*. The ends of the cables *b* have connected to them screw bolts *d* that are passed through holes formed therefor in the end laths *e* which are thicker and more substantial than the others, as shown in Fig. 2. Below these end laths the bolts *d* are fitted with nuts *f* by manipulation of which the ropes can be so tightened as to force all the laths closely into contact with each other independently of any supporting members. To allow of the necessary sliding movement while this is being done the laths *e* are yieldingly held between the heads *g* of hook bolts *h* and the floor joist *k*. Any desired number of cables *b* may be arranged at intervals along the length of the building.

To protect the cables and to secure the

laths firmly thereto while allowing them to slide thereon, the said cables with advantage are threaded through holes *m* formed therefor in the several laths near the outer sides thereof as shown in Fig. 3.

The free end of the cable may, as shown in Fig. 3, be passed through a hole formed therefor in a floor joist *k* and terminate in a screwed rod *n* on which is screwed a nut *o* bearing upon a metal plate or washer *p* at the bottom of the floor joist. It will be understood that with an arrangement in which the cable passes through a floor joist, as shown in Fig. 3, the laths *a* are free to slide toward each other when the cables *b* are tightened in order to render the structure self-supporting independently of any supporting members, so that if supporting members are provided they must be such as not to interfere with the said necessary sliding movement.

Numerous modifications may be made without departure from the invention as will be understood, for example the strips, bands or cables may either serve the double purpose of a means of forcing the laths together and a connection for the several laths, or bands, strips or cables may be employed for connecting the laths in addition to bands, strips or cables, which by being tightened force the laths toward each other. Wedges, springs, or other devices may be employed in any of the constructions described for taking up slack due to contraction and generally for adjustment due to shrinkage or other causes.

What I claim is:—

1. A portable building structure section constructed of slats arranged side by side and so close together and in such relation to a flexible connection that if curved or arched the flexible connection will be put under stress and the abutting edges of the slats will be caused to bear against each other, whereby the slats support each other, said section embodying a binding cable backing the same throughout the length thereof and confined thereto, said cable provided with adjustable end means for tightening the cable with respect to the section to force the abutting edges of the slats toward each other, in combination with means to maintain the relative positioning of the section

ends when the section is arched and thereby render it self supporting.

2. A portable building structure comprising a section constructed of slats arranged side by side and so close together and in such relation to a flexible connection joining them, that if curved or arched said connection will be put under stress and the abutting edges of the slats will be caused to bear against and mutually support each other, said section embodying a longitudinal binding cable backing said slats and provided with adjustable end means for tightening said section longitudinally with respect to the cable, the end slats of said section being threaded on said cable and movable thereon to permit positioning thereof during tightening of the cable when the section is arched, in combination with means to removably receive the ends of the section and maintain the relative positioning thereof when the section is arched and tightened and thereby render it self supporting.

3. In a portable building such as described by claim 2, the slats being relatively movable longitudinally of the longitudinal backing cable in positioning themselves during tightening of the cable when the section is arched, the cable having the end adjusting means extending loosely through an end slat and abutting the same to tighten the section with respect thereto, in combination with means removably receiving the section ends and maintaining the lateral positioning thereof when the section is arched and thereby rendering it self supporting, said means constructed and arranged to permit relative vertical sliding movement of the section end during tightening of the cable.

4. In a portable building structure such as described by claim 2, the means for maintaining the ends of the arched section against spreading comprising a beam and vertical guides spaced therefrom, the end of the section being arranged between said beam and guides and vertically adjustable with respect thereto.

Signed at London, England, this second day of January, 1919.

CHARLES STAFFORD WAKEFIELD.
